DESK ADVERTISING PERPETUAL CALENDAR

Max Hopp, New York, N. Y.

Application May 11, 1949, Serial No. 2,582

Term of patent 14 years

(Cl. D74—5)

To all whom it may concern:

Be it known that I, Max Hopp, a citizen of the United States and resident of New York city, in the county of New York, State of New York, have invented a new, original, and ornamental Design for Desk Advertising Perpetual Calendar, of which the following is a specification, reference being had to the accompanying drawing, forming a part thereof, and of which Fig. 1 is a perspective view showing the front side and an end of a desk advertising perpetual calendar embodying my new design with removable card stacks shown in dotted lines. Fig. 2 is a perspective view showing the rear side and an end of the desk advertising perpetual calendar shown in Fig. 1 with the card stacks removed, and Fig. 3 is a cross-sectional view taken on line 3—3 in Fig. 1.

The essential features of my design reside in the part shown in full lines.

I claim:

The ornamental design for a desk advertising perpetual calendar, as shown and described.

MAX HOPP.
